UNITED STATES PATENT OFFICE.

DENNIS B. MARTIN, OF NEW HAVEN, CONNECTICUT.

SYRINGE-TUBE SINKER.

SPECIFICATION forming part of Letters Patent No. 447,574, dated March 3, 1891.

Application filed November 17, 1890. Serial No. 371,679. (No model.)

To all whom it may concern:

Be it known that I, DENNIS B. MARTIN, of New Haven, in the county of New Haven and State of Connecticut, have invented a new 5 Improvement in Sinkers for Syringe-Tubes; and I do hereby declare the following, when taken in connection with accompanying drawings and the letters of reference marked thereon, to be a full, clear, and exact description of the same, and which said drawings constitute part of this specification, and represent, in—

Figure 1, a syringe with the sinker attached to the end of the inlet-tube; Fig. 2, a vertical 15 central section through the sinker and a portion of the tube attached.

This invention relates to an improvement in the device which is applied to the inlet end of a syringe-tube as a means for sinking or holding that end of the tube below the surface of the fluid which the syringe is to draw, and also to hold the end of the tube distended for the free admission of such fluid. It is desirable to provide these sinkers or the termination for the inlet end of a syringe-tube with some device by which the syringe as a whole may be suspended from that inlet end, so that when hung up by that end the valves will open, so that the syringe will completely drain. These sinkers at the termination of the inlet end of the syringe-tube have been made from cast metal provided with a hook by which to suspend the syringe; but such cast-metal termination 25 is objectionable because of its inflexibility, and the hook is also objectionable because of its great liability to accidentally catch upon objects.

The object of my invention is to produce 40 a sinker for syringe-tubes which shall be of substantially the same material as the tube itself, and therefore flexible and elastic, and provided with a loop made as an integral part of the sinker, and therefore, like the sinker itself, flexible and elastic; and in such a sinker, as more fully hereinafter described, and particularly recited in the claim, my invention 45 consists.

A represents the bulb of the syringe; B, the 50 inlet-tube, and C the exit-tube, all of common construction.

D represents the sinker, made from india-rubber or any of its known equivalents, so as to be elastic and flexible. It consists of

a tubular body of a diameter somewhat 55 greater than the internal diameter of the tube to which it is to be attached, and the attaching end is constructed with an annular bead a, so that when the tube B is expanded and drawn over the said bead onto the body 60 of the sinker it will clasp the said body and bead, so as to firmly attach the sinker to the tube. The body is provided with an annular enlargement E, which is in the form of a large bead, and so as to make a support for 65 the sinker when lying on the bottom of a vessel, so as to raise the inlet end of the sinker somewhat from the bottom of the vessel. The tubular body is open from end to end, so as to afford free entrance through the body into the 70 tube B.

At the outer end the body is constructed with a ring-shaped loop F, made of the same material and integral with the body, and spans the opening into the tube, as seen in 75 Fig. 2. The loop is flexible, so that it may be readily turned away, from over the opening, should occasion require, and its flexibility prevents its accidental engagement with objects interfering with the general use 80 of the syringe, and the loop serves as a most convenient means of hanging the syringe, much less objectionable than the usual rigid hook, because of the less liability of accidental detachment when it is hung. 85

Another and great advantage of this soft flexible elastic sinker over the hard sinker is in the fact that the soft sinker avoids the rattling which necessarily follows the contact of the hard-material sinker with the vessel 90 which contains the fluid, the sinker of this invention being noiseless.

I claim—

The herein-described sinker for syringes, consisting of a tubular body made from 95 elastic flexible india-rubber adapted at one end for attachment to the inlet-tube of the syringe, and at its opposite end constructed with a loop made of the same material and integral with the body, substantially as described.

In testimony whereof I have signed this specification in the presence of two subscribing witnesses.

DENNIS B. MARTIN.
